NOZZLE AND METHOD OF MAKING THE SAME

Joe L. Barnes, Des Moines, Iowa, assignor to L. R. MacKenzie, Incorporated, Des Moines, Iowa, a corporation of Delaware

Application April 12, 1937, Serial No. 136,394

3 Claims. (Cl. 299—154)

The object of my invention is to provide a nozzle and a method of making the same.

More particularly, it is my object to provide a nozzle of very simple and inexpensive construction, which is especially adapted for handling various liquids including, for example, asphalt emulsion, which is exceptionally hard to dispense in the form of a spray.

In attempting to produce a fine spray of various liquids, considerable difficulty has been encountered in an attempt to find a satisfactory discharge nozzle. In the case of many liquids, a spray nozzle of the ordinary garden hose type, which uses a ball, soon clogs up. Where a nozzle is employed with a round hole or a series of round holes, I find that when the holes are fine enough to produce a fine spray, they soon clog up and if the holes are made large enough to avoid clogging, it is impossible to get a fine spray.

I have discovered that by the particular structure of nozzle herein explained, I can use the nozzle for handling many liquids, including asphalt emulsion and can produce a very fine spray with no difficulty on account of clogging.

I also find that with a nozzle of the kind herein explained, the pressure can be varied for determining the spread of the spray.

I also find that by a very simple modification in the nozzle, it can be varied for handling different quantities of liquid per minute.

It is therefore my object to provide a nozzle of a construction which will not clog up and which will afford a fine spray of various materials.

A further object is to provide a simple method for making such a nozzle.

With these and other objects in view, my invention consists in the construction, arrangement and combination of the various parts of my nozzle and in the method of making the same, whereby the objects contemplated are attained, as hereinafter more fully set forth, pointed out in my claims, and illustrated in the accompanying drawing, in which:

Figure 1 is a side elevation of a nozzle embodying my invention installed in connection with a supply tube and control valve.

Figure 2 is a top or plan view of the nozzle with an illustration of the spray formed thereby.

Figure 3 is a similar view showing liquid flowing from the nozzle under light pressure and at the beginning of the formation of the spray at right angles to the slot.

Figure 4 is a perspective view of the nozzle.

Figure 5 is a detailed, sectional view on the line 5—5 of Figure 1.

Figure 6 is a detailed, sectional view taken on the line 6—6 of Figure 5; and

Figure 7 is a perspective view of the nozzle after one stage in the manufacture.

After experiments with various liquids with many kinds of nozzles, all of which were unsatisfactory, because of the difficulty in getting a nozzle which would afford a fine spray, and yet would not clog, I designed the nozzle herein shown.

The method by which the nozzle is made is very simple.

A piece of tubing or the like indicated by the reference numeral 10 has one end placed in a die and flattened, to bring the two edges tightly together along the line 11. They may be pressed together tightly enough, so that they are practically leak-tight.

They are also pressed together for a short distance from the extreme end as indicated at 12 in Figure 5. Ordinarily I press them together for about one-eighth of an inch.

The form of the article at this stage of its manufacture is illustrated in Figure 7.

The corners may then be ground off to make a more presentable product.

To form the nozzle opening, I grind or file off the central part of the compressed edges of the nozzle to form the curved notches 13, shown in Figure 4. This leaves a slot 14, such as is shown in Figure 4, which is curved from its center upwardly and outwardly to its end.

The opposite end of the tube is preferably threaded as at 15 to fit into the internal threaded fitting 16 on a suitable valve 17. The valve 17 may be connected with a supply pipe 18 and may be controlled by a handle 19.

Assuming that the liquid used with the nozzle is supplied through the tube 18 under pressure, and the valve is slightly opened, it will be observed that the fluid 20 starts to flow from the nozzle opening slot 14 and as the pressure is increased, the fluid begins to extend into a fan shape at right angles to the length of the slot 14 as illustrated in Figure 3.

The fluid apparently flows through the tube 10 toward the nozzle opening. Some of the fluid passes into the wider part of the tube at the nozzle end. As indicated by the arrows in Figure 6, some of the fluid probably passes out through the central part of the slot, but the fluid so emerges from the slot as to form the fan-shaped spray at right angles to the length of the slot.

I have found that in a nozzle of the shape

- here shown, I can provide a slot of sufficient size that it will not clog up when viscous liquids, for example, are used, and yet the liquid will discharge from the nozzle in a very fine spray.
- 5 The fineness of the spray can be regulated by the pressure supplied and by the degree to which the valve is opened.

For supplying different amounts of liquid, I use various sizes of nozzles, and by varying the size of the slot 14, the discharge capacity can be regulated.

The length of the slot 14 is always less than the length of the closed ends of the nozzle, so that there is a closed portion as indicated at 22 15 at the end of the nozzle and at each end of the slot 14.

I claim as my invention:

1. A method of forming a nozzle for use in spraying various liquids, comprising the steps 20 of flattening the end of a tube to bring the edges snugly together, and then forming rounded notches in the adjacent closed edges, for thus forming an open slot of less length than the transverse length of the closed end of the tube.

2. A nozzle having a tubular body flattened at one end to bring its edges tightly together, each of the adjacent edges having a curved notch, the notches being of similar shape, whereby there is formed a slot terminating at its ends short of the extreme ends of the closed edges of the tube.

3. In a nozzle for forming a fan-shaped spray, a tubular body having one end pressed and flattened to bring the two edges tightly together for a short distance lengthwise of the tube, each of 10 the adjacent edges having a curved notch, the notches being of similar shape and of a depth extending from the free end of the nozzle beyond the flattened portions, whereby there is formed a slot in the end of the tube terminating at its 15 ends short of the extreme ends of the closed edges of the tube, said nozzle being such that by varying the depths of the notches, the size of the slot may be varied for varying the capacity of the nozzle.

JOE L. BARNES.
